Claims priority, application Sweden
October 18, 1950

4. Claims. (Cl. 98—38)

1

The present invention relates to new and useful improvements in devices for regulating the relative proportions of the conditioned and non-conditioned parts of a gaseous medium flowing through a duct or channel.

The general object of the invention is to provide a regulating device of the stated character which is of a superior construction and operation than heretofore.

According to the present invention, the conditioning means is disposed in the duct or channel and is enclosed by a casing having an outlet opening for the conditioned part of the medium which is controlled by a valve disc. Fastened to the top of the conditioner casing is a flexible plate valve for controlling the proportions of the medium which are caused to flow through the conditioning means and non-conditioning section of the duct or channel, respectively. The flexible plate valve extends entirely between the two opposite sides of the duct or channel and has its front edge at the inlet end of the duct extending downwardly partially across the inlet opening for cooperative association with a fixed wall part of the duct. The inlet end of the flexible plate valve and the aforesaid valve disc at the outlet from the conditioning means are mechanically interconnected by levers which are arranged upon actuation in one direction, to cause the flexible plate valve to open with respect to the adjacent fixed duct wall and the valve disc to open with respect to the conditioning means outlet to thereby relatively increase the proportion of the medium entering the duct to flow through the conditioning means. Conversely, upon actuation of the levers in the other direction the plate valve and valve disc are caused to move to their respective closed positions thereby decreasing relatively the proportion of the inlet air which is caused to flow through the conditioning means and increasing the proportion that is caused to by-pass the conditioning means.

Other features of the invention will be apparent from the following description and reference to the accompanying drawings, in which:

Fig. 1 is a vertical sectional view longitudinally through a duct or channel incorporating the present invention; and

Fig. 2 is a view similar to Fig. 1 illustrating a modified construction of the invention.

Referring to the drawings (Fig. 1), the duct or channel is designated 6—34 and is supported by means of angle irons or the like 26 and 39. Preferably the duct is constructed of sheet metal and insulated. The duct lower wall or panel com-

2

prises an outer sheet member 62 which is provided with suitable insulation 63 and this wall or panel may be readily removed for inspection and servicing of parts within the duct simply by removing screws 65. The upper wall or panel of the duct comprises an outer plate 16 and an inner plate 15 between which is provided a suitable thickness of insulating material 21. The front and rear edges of the insulating material are provided with protective flanges 27.

The duct or channel has a common inlet D—F at its right hand end as viewed in the drawings. The medium entering the duct or channel through the inlet opening D—F is caused to flow proportionately through an inlet opening E—F and suitable conditioning means 54 and/or through an opening D—E and a passage 13 which by-passes the conditioning means, according to the position of a flexible plate valve 17. In the drawings the plate valve 17 is shown entirely closed with respect to the by-pass 13 so that all of the incoming medium is caused to pass through the opening E—F and the conditioning means 54.

In the embodiment of the invention which is shown in Fig. 1 of the drawings, the conditioner 54 consists of a radiator device having heating coils 55. However, other conditioning means may be employed, such as, for example, a cooling element, humidifying means, or the like, without departing from the invention. As shown the conditioner 54 is enclosed by a housing 19 having an inlet opening G—H and an outlet opening 59. The conditioner construction is symmetrical which may be demounted as a unit and positioned for connection of the coils at either side of the duct or channel. By removing the lower duct panel as previously described, the conditioner may be removed by releasing the screws 52 and 64.

At the inlet end of the duct an upstanding wall part 38 is provided which supports an angular plate 35 that may be raised or lowered as required. This may be accomplished by loosening a screw 26 which extends through an elongated slot 37 in the plate 35. The wall part 38 is insulated as indicated at 38a. By adjustment of the vertical position of the plate 35 the size of the inlet opening E—F in the limit open position of the plate valve 17 may be predetermined.

In the construction shown, the conditioner housing outlet 59 opens into a chamber 60 having an outlet opening B—C defined by the oppositely curving edge portions 3 and 4 of the chamber end wall 2. This outlet opening B—C is

controlled by a disc valve 5 having an insulating gasket 5a. The valve 5 is mounted on an arm 58 which in turn is carried by an angular member 56 that is pivotally suspended from a support 11 by means of a pivot 12. The support 11 is fastened by screws 10a and 10b to an insulator 14.

As shown in Fig. 1, the flexible plate valve 17 extends obliquely upward from the top of the housing 19 and its free end is disposed for positioning cooperatively with respect to and between the ceiling duct wall member 15 and the angular plate 35. By this construction the flow area through the by-pass passage 13 is made to increase gradually lengthwise of the duct or channel thereby minimizing noise that otherwise might result from the flow and intermixing of the two streams of the medium in the duct. For this purpose also, the edge of the flexible plate valve at the inlet to the duct is provided with a bulbous configuration 33 to minimize resistance to the flow of the medium inwardly of duct or channel.

In accordance with the invention the two valves 17 and 5 are operated together. To this end, a lug 20 is mounted on the underside of the plate valve 17 adjacent its free end and connected to this lug is a actuator rod 25 the upper end 24 of which is projected through an opening in the lug 20. The lower end of the rod 25 is connected to a segment arm 45 which is pivotally mounted on a shaft 43 that is fixedly mounted in an upright plate 41. The outer portion of the arm 45 is provided with a plurality of openings in which the lower end of the rod 25 may be selectively engaged to effect the required movement of the flexible plate valve 17. The segment arm 45 and the arm 58 are interconnected by means of a tie-rod 51. The construction and arrangement of the valves 5 and 17 together with their common actuating means as shown in the drawings is such that in the fully open position of the flexible plate valve 17, i. e., maximum opening at E—F, the quantity of the medium caused to pass through the conditioning means 54 is approximately one-half as great as the amount of the medium which is caused to flow through the by-pass 13 when the opening E—F is entirely closed by the plate valve 17. An advantage of this construction is that no separate regulating valve is required for the inlet to the conditioning means 54.

In the modification shown in Fig. 2 of the drawings, the construction is the same as that previously described except for the location of the outlet 3a for the conditioned portion of the medium and the mechanical interconnections provided between the disc valve 5 and the flexible plate valve 17. In this embodiment the valve disc 5 may be moved into closing engagement with outlet 3a after the valve 17 is closed with respect to the by-pass 13.

According to the modified construction an arm 45a is pivoted on a shaft 43a. The upper end of this arm 45a is connected to a lug 20a at the underside of the plate valve 17 by means of a rod 25a which has its lower end portion selectively

engaged in one of a series of openings 47a, 48a, 49a and 50a in the arms 45a and has its upper end similarly engaged in one of a series of openings in the lug 20a. This construction permits continued movement of the mechanical interconnection between the valves 5 and 17 so that the valve 5 may be moved into closing engagement with outlet opening 3a after the plate valve 17 has been moved to closed position with respect to the by-pass 13, thereby to entirely shut-off flow through the duct or channel.

We claim:

1. A device for regulating the proportions of the conditioned and non-conditioned portions of a gaseous medium comprising, a duct through which the medium is adapted to flow having an inlet opening at one end and an outlet at the other end, partition means in said duct defining therein a by-pass passage and a conditioning passage having an inlet and an outlet opening, conditioning means in said conditioning passage, a disc valve cooperable with said outlet opening of the conditioning passage, a flexible plate valve mounted in the by-pass passage and extending obliquely therein crosswise of the by-pass passage with its free end portion confronting the duct inlet opening and selectively positionable between opposite sides of the duct inlet opening to cause the incoming medium to flow through the conditioning and by-pass passages in proportions ranging from zero to maximum in the respective passages, and means mechanically interconnecting said flexible plate and disc valves for conjoint operation thereof constructed to cause the disc valve to move in opening relation to the conditioning passage outlet as the flexible plate valve moves in closing relation with the by-pass passage.

2. A device as claimed in claim 1, wherein the conditioning means is a heat exchanger and the conditioning passage occupies the lower portion of the duct with the flexible plate valve extending longitudinally of the upper portion of the duct between the partition means and the top wall of the duct.

3. A device as claimed in claim 1, wherein means is provided in the duct defining a chamber at the outlet from the conditioning means in which the disc valve is disposed and having a funnel shaped discharge opening into the duct for the conditioned portion of the medium.

4. A device as claimed in claim 3 wherein the mechanical interconnection between the flexible plate valve and the disc valve is actuatable, after the plate valve is closed with respect to the by-pass passage, to move the disc valve into closing relation with the funnel shaped discharge opening from the chamber.
